UNITED STATES PATENT OFFICE.

JAMES S. FOX, OF WOODSTOCK, VERMONT.

IRON FENCE-POST.

SPECIFICATION forming part of Letters Patent No. 269,844, dated January 2, 1883.

Application filed January 14, 1882. (No model.)

To all whom it may concern:

Be it known that I, JAMES S. FOX, a citizen of Ontario, Canada, residing at Woodstock, in the county of Windsor and State of Vermont, 5 have invented certain new and useful Improvements in Iron Fence-Posts, of which the following is a full, clear, and exact description, reference being had to the accompanying drawings, making part of this specification, in which—

Figure 1 is a side elevation of an iron fence-post constructed in accordance with my invention. Fig. 2 is a longitudinal vertical section through the center of the same. Fig. 3 is a 15 perspective view of the shoe detached. Fig. 4 is a transverse section on the line $x-x$ of Fig. 2. Fig. 5 is a transverse section on the line $y-y$ of Fig. 1. Fig. 6 represents modifications of my invention.

20 My invention has for its object to so improve the construction of iron posts for barbed-wire fences as to greatly increase their strength and durability, and also render them much stiffer or firmer when inserted in the ground 25 than heretofore; and my invention consists in a fence-post composed of a single continuous semicircular piece of metal which is bent double at its center, so that the edges of the two parts come together, and which has a metallic foot-piece secured to its lower end.

30 The second part of my invention has for its object to facilitate and expedite the operation of setting the post in the ground, thus saving much time and labor; and it consists in the 35 combination, with a fence-post constructed as above described, of a pointed flanged shoe composed of two separate portions secured to the lower ends of the two vertical portions of the tubular post, the outer edges of the flanges 40 diverging from the bottom or point upward, the shoe thus enabling the post to be readily driven into the ground, while the flanges extend its area and consequent bearing-surface and render the post stiff and immovable when 45 set.

In the said drawings, A represents an iron fence-post, which is composed of a piece of angle-iron of suitable length bent double at 50 b , thus forming two parallel vertical portions or bars, $c c$, which are fitted closely together

and form a tubular post of rectangular form in cross-section, as seen in Fig. 5, which possesses the advantages of great strength, stiffness, and durability, combined with lightness, small cost, and immunity from liability to destruction by fire. 55

Between the lower ends of the portions $c c$ of the post are secured by a single bolt or rivet, d , a pointed shoe, B, which is composed of two separate triangular wrought-iron plates, $e e$, 60 each side of each plate being bent outward at an angle, as seen in Figs. 3 and 4, forming flanges 10, the outer edges of which diverge or incline outward from the bottom toward the top, while a central flat portion, 12, is left of 65 a width corresponding to that of the portion c of the post, which is thus confined by the rivet d tightly between the angles 13 of the bent plate e , and in this manner prevented from moving laterally or getting out of place, the two 70 plates e being still further secured together by a rivet, f , near the point of the shoe. Instead of bending the sides of the plate e at the angles 13, as shown, to form flat flanges 10, these sides may each be bent in a curve to 75 form curved flanges, if preferred. This shoe B greatly facilitates the operation of setting the post, it being merely necessary to drive the shoe into the ground until its upper end is flush or a little beneath its surface, which can 80 be most conveniently accomplished by the employment of a short piece of heavy metal tubing slipped over the post A and moved up and down thereon for the purpose of delivering the necessary blows upon the upper end 85 of the shoe; but these blows may be delivered by a hammer or other suitable instrument, if preferred; and it will be seen that by the employment of this shoe the necessity of digging post-holes, as heretofore, is entirely obviated, 90 thereby effecting a material saving in time and labor, while the projecting flanges 10 greatly extend the area of the shoe, and its consequent bearing or holding surface in the ground, after the latter has been rammed or 95 stamped down around it, thus imparting great stability to the post and rendering it capable of resisting a great strain.

The post A, in lieu of being composed of a single piece of iron doubled over at b , as shown, 100

may be formed of two entirely separate pieces, similar to the portions *c c*, fitted together in the same manner to form a tube, in which case they would be held together at their lower ends only by the bolt *d* or other device used for securing them to the shoe *B*; and, instead of making the portions *c c* of angle-iron, they may be formed of iron bent or rolled into semi-circular or curved form in cross-section, so that when put together they will form a tubular post of circular or oval form in cross-section, as seen in Fig. 6.

Any suitable clamping or fastening device may be employed in connection with my improved post for securing thereto the barbed wires employed in forming the fence.

What I claim as my invention, and desire to secure by Letters Patent, is—

1. As a new article of manufacture, a fence-post formed of a single continuous tubular

piece of metal which is bent double at its center, so that the edges of the two parts come together, and which has a metallic foot-piece secured to its lower end, substantially as shown.

2. A tubular fence-post, *A*, composed of a single bar of angle-iron, or iron of semicircular or curved form in cross-section, bent double at *b* to form two parallel vertical bars or portions, *c c*, in combination with the pointed shoe *B*, composed of two separate plates or portions, *e e*, bent to form flanges *10*, and secured to the lower ends of the bars *c c*, substantially as and for the purpose described.

Witness my hand this 2d day of January, 35
A. D. 1882.

JAMES S. FOX.
